United States Patent Office

Des. 224,858
Patented Oct. 3, 1972

224,858

CHAIR

Kenneth W. Leino, East Detroit, Mich., assignor to Borg-Warner Corporation, Chicago, Ill.

Filed Nov. 23, 1970, Ser. No. 26,118

Term of patent 14 years

Int. Cl. D6—02

U.S. Cl. D6—65

FIG. 1 is a perspective view of a chair showing my new design;

FIG. 2 is a top plan view thereof;

FIG. 3 is a front elevational view thereof;

FIG. 4 is a bottom plan view thereof;

FIG. 5 is a left side elevational view thereof; and FIG. 6 is a rear elevational view thereof.

I claim:

The ornamental design for a chair, substantially as shown.
